UNITED STATES PATENT OFFICE.

CHARLES T. KELLY, OF HARRIMAN, TENNESSEE, ASSIGNOR TO D. M. SMALLMON AND THOMAS L. CATES, OF HARRIMAN, TENNESSEE.

MEAT-SACKING MACHINE.

No. 822,956.

Specification of Letters Patent.

Patented June 12, 1906.

Application filed October 27, 1904. Serial No. 230,211.

To all whom it may concern:

Be it known that I, CHARLES T. KELLY, a citizen of the United States, residing at Harriman, in the county of Roane and State of Tennessee, have invented a new and useful Improvement in a Meat-Sacking Machine, of which the following is a specification.

This invention relates to a device adapted to hold meat and a sack into which the meat is to be placed and is provided with means for holding the sack in place, for tilting the movable platform upon which the meat rests, and for automatically releasing the sack after the meat has passed therein.

15 The object of the invention is to facilitate the sacking of meat; and it relates also to the construction of a portable meat-sacking machine adapted to be placed in position for use upon an ordinary pair of scales.

20 The invention consists of the novel features of construction and combination of parts hereinafter fully described, particularly pointed out in the claims, and shown in the accompanying drawings, in which—

25 Figure 1 is a perspective view showing the device in operation. Fig. 2 is a vertical side elevation. Fig. 3 is a vertical section, the parts being in elevation, showing the position of the movable parts when the meat-holding platform is tilted into an inclined position. Fig. 4 is a plan view of the platform. Fig. 5 is a detail sectional view of a portion of the platform, showing the construction of the sack-holding hooks.

30 In constructing my device I employ a base comprising the board A, held between two transverse end pieces A', and upon the base A is arranged a standard B, braced by the brace-rods B'. The standard B is slotted intermediate its ends, as shown at B², and above the slot is arranged a transverse bore B³. Metal plates C are secured upon opposite sides of the standard B and project above the same. The platform D is of any suitable construction, and I have shown it as an open frame formed of a plurality of timbers arranged transversely with respect to a second set of timbers. The platform D carries on its under face metal brackets D', each having 45 an angled portion D², which extends down and overlaps the plate C, and a pivot-pin D³, passing through the upwardly-projecting portions of the plate C, and the angled por-

tions D² of the brackets D' pivotally connect the platform D to the standard B. The 55 platform D also carries a segment E, formed on the arc of a circle having the pivot-pin D³ as its center. The segment E works through a slot B², and upon each side of said slot carries projecting legs E', which act as 60 stops and limit the tilting movement of the platform D. Brackets F are arranged upon one side of the standard and in these brackets slide the vertical bifurcated portion of an angled plate F', the said bifurcated portion 65 straddling the segment E and when in its highest position engaging a notch E², formed in the lower edge of the segment midway the legs E', thereby locking the platform D in a horizontal position. A lever G is pivoted 70 adjacent the angled plate F' and is twisted to form a foot-pedal G', and a link G² connects the lever F with the outer free end of the plate F'. A spring H is connected at one end to the free end portion of the plate F' and 75 at its opposite end to a bracket H', carried by the standard B.

Opposite side members of the platform D are slotted longitudinally, as shown at J, and in each of these slots is pivoted a lever J', 80 having on its free end a T-head terminating at one end in a hook J² and at the opposite end in a projection J⁵. Adjacent the T-head a curved slot J³ is formed, into which projects a stop-pin J⁴, placed vertically on the 85 bottom of the slot J. The spring J⁸ normally holds the hook J² in a position projecting from the slot or recess J. The pulleys K are arranged between the said levers upon the front transverse timber or bar of the platform, and cords or wires J⁶ are connected to the projecting portions J⁵ of the levers J' and are carried over the pulleys K and joined to a cable, cord, or wire J⁷. The cable J⁷ passes over a plurality of pulleys K', secured to opposite sides of the standard B, and also passes through the bore B³, formed in the standard B, and is connected at its rear end to an eye K², carried by the rear member of the platform. 100

In use the device above described is placed upon a pair of ordinary scales and the meat to be sacked is placed on the platform D and the sack has its mouth portion opened and one edge in engagement with the lower face 105 and sides of the platform D adjacent its

lower edge, in which position it is engaged by the hooks J^2 and held in position on the platform. As soon as the mouth portion of the sack has enveloped the ends of the piece of meat to be sacked or has been spread open so as to receive the meat the operator depresses the lever G , drawing down the angled plate F' , and thereby unlocking the platform, which can be readily swung into an inclined position, and the meat will slide into the sack. This swinging movement of the platform will draw the cable J^7 rearwardly by reason of the elevation of the rear end of the platform, and the hooks J^2 will be drawn inwardly by the cords J^6 , thus automatically releasing the sack from engagement with the said hooks. To return the parts to their normal position after being inclined, I show a weight L , carried by the segment E adjacent the rear end of the platform.

Having thus fully described my invention, what I claim as new, and desire to secure by Letters Patent, is—

1. A device of the kind described comprising a tilting platform, outwardly-projecting hooks carried by the said platform, means for locking the platform against tilting movement, and means for automatically drawing the hooks inwardly when the platform is tilted.
2. A device of the kind described comprising a slotted standard, a platform pivotally connected to the standard, a segment carried by the platform and working in the slot of the standard, means for locking the said segment against movement, and means for automatically returning the segment to its

normal position after each movement of the platform.

3. A device of the kind described comprising the platform adapted to be tilted into an inclined position, pivoted hook members carried by the platform, means for automatically actuating said hook members upon movement of the platform and means for automatically returning the platform to a horizontal position.

4. A device of the kind described comprising a standard, a platform pivotally connected to the upper end of the standard, the said standard being slotted, a segment carried by the platform and working through the slot, stop-legs carried by the segment on opposite sides of the standard, the said segment being notched intermediate the legs, a spring-actuated movable plate adapted to engage said notch, means for withdrawing the plate from engagement with the notch, hooks carried by the platform and means for automatically returning the platform to a horizontal position.

5. A device of the kind described comprising a standard, the platform pivotally connected thereto, slots being formed in opposite side members of the said platform, pivot-hook members arranged in said slots and adapted to normally project therefrom, a plurality of pulleys and cables connected to the hook members passing from said pulleys and adapted to retract the hook members upon swinging movement of the platform.

CHARLES T. KELLY.
